UNITED STATES PATENT OFFICE.

JAMES PEARS TRYNER, OF DENVER, COLORADO.

SPECTACLES.

SPECIFICATION forming part of Letters Patent No. 375,964, dated January 3, 1888.

Application filed March 10, 1887. Serial No. 230,393. (Mod.1.)

To all whom it may concern:

Be it known that I, JAMES PEARS TRYNER, of Denver, in the county of Arapahoe and State of Colorado, have invented new and useful 5 Improvements in Spectacles, of which the following is a full, clear, and exact description.

The invention consists of the construction and arrangement of various parts and details and combinations of the same, as will be here- 10 inafter fully described, and then pointed out in the claims.

Reference is to be had to the accompanying drawings, forming a part of this specification, in which similar letters of reference indicate 15 corresponding parts in both the figures.

Figure 1 is a plan view of my improvement, with parts in section; and Fig. 2 is a side elevation of the same.

A represents a pair of spectacles, of which 20 B is the glass-frame, D D are two short arms hinged to the ends of the frame B and provided with longitudinal apertures.

E are the temples, which are cut to a proper length to suit the wearer at the time of pur- 25 chase, and driven into the apertures in the arms D, where they are immovably held by friction. The arms D thus form the connec-

tion between the temples and the glass-frame. The temples are much shorter than usual, and have their free ends provided with balls F, of 30 any suitable material, the balls being of greater size than the usual balls, so that they engage the front rims of the ears near their lower ends. The free ends of the temples have very short bends.

Having thus fully described my invention, I claim as new and desire to secure by Letters Patent—

1. The combination, with the glass-frame, of the hinged temples bent short at their free 40 ends, and provided with large balls to engage the front rims of the ears of the wearer, substantially as set forth.

2. The combination, with the glass-frame and the longitudinally-apertured arms hinged 45 thereto, of the short temples secured immovably at their inner ends by friction within said apertures, and having the large balls at their free bent ends to engage the front rims of the wearer's ears, substantially as set forth.

JAMES PEARS TRYNER.
